UNITED STATES PATENT OFFICE.

NATHAN B. TEMPLE, OF ROCKINGHAM, NORTH CAROLINA, ASSIGNOR OF ONE-HALF TO
JOHN L. HAWLEY, OF ROCKINGHAM, NORTH CAROLINA.

TRAIN SLACK-ADJUSTER.

1,257,766.

Specification of Letters Patent. Patented Feb. 26, 1918.

Application filed June 8, 1917. Serial No. 173,593.

To all whom it may concern:

Be it known that I, NATHAN B. TEMPLE, a citizen of the United States, residing at Rockingham, in the county of Richmond 5 and State of North Carolina, have invented a new and useful Train Slack-Adjuster, of which the following is a specification.

The object of this invention is a train slack adjuster wherein buffer bars are coöperatively associated with air cushioned pistons, and the objects of the invention are, first, to provide means for retaining the cars of a train uniformly spaced apart, second, to provide means for automatically adjusting 15 the spacing element when rounding curves, third, to provide means for preventing sudden shocks in a train, fourth, to provide a slack adjuster system composed entirely of parts already in use in train equipment, fifth, 20 to provide a slack adjuster which will permit easy coupling and uncoupling of a train, sixth, to provide a slack adjuster that is under control of the engineer at all times, seventh, to provide a simple and efficient 25 train slack adjuster.

With the foregoing and other objects in view, which will appear as the description proceeds, the invention resides in the combination and arrangement of parts and in 30 the details of construction hereinafter described and claimed, it being understood that changes in the precise embodiment of the invention herein disclosed can be made within the scope of what is claimed, without 35 departing from the spirit of the invention.

A practical embodiment of the invention is shown in the accompanying drawings, wherein:—

Figure 1 is a side elevation of an adjuster 40 constructed in accordance with the present invention, the car platform to which the device is shown attached being in section and portions broken away;

Fig. 2 is a plan view of the same, the 45 flooring removed, the car sills being in section and portions of the device broken away;

Fig. 3 is a diagrammatic view of the system;

Fig. 4 is a plan view illustrating the position assumed by the device in rounding a curve.

Referring to the drawings by numerals of reference:—

The device is herein shown attached to the 55 platform, indicated generally at 1 and 2, of

two similar cars. The platforms contain the usual end sills 3, from which extend the longitudinal supports 4 carrying the draw bars 5, provided with the usual coupling heads 6.

Secured beneath the flooring of the platform 1 and supported by brackets 7, or otherwise, are similar cylinders 8—8, which are arranged horizontally one on each side of the draw bar 5 and parallel thereto. In 65 each cylinder 8 reciprocates a piston 9, secured to a piston rod 10. Each piston rod 10 projects through an aperture in the cylinder head in which it has a sliding fit, and through an aperture formed transversely of the sill 3. A coiled spring 11 surrounds each piston rod 10 and is confined between the piston 9 and the head 12 of the cylinder 8. The outer end of each piston rod 10 is 70 pivotally connected to a lug 13 which extends laterally from a point adjacent the end of a buffer bar 14. These lugs 13 may be rigidly secured to the buffer bar, or, to insure proper play in rounding curves, they may be as here indicated each formed with a base block 15 75 having beveled edges to take into a dovetail groove 16 formed in each end of the buffer bars 14, or any other form of connection suitable for this purpose may be used. Each buffer bar 14 has secured thereto by rivets 80 or otherwise a rearwardly extending plate 17, which overlies the end sill.

The inner head 18 of each cylinder is formed with an aperture communicating with the bore of a nipple 19 which extends 90 from the head 18, or other suitable connecting means. Each nipple 19 has suitable connection with a short pipe 20 each of which is connected with a branch pipe 21 extending transversely of the car from a T joint 22 in 95 the main line 23, which line extends longitudinally of each car. The line 23 is connected between cars by the usual air pipe coupling indicated at 24. This main line is also provided with the usual stop cocks 25 100 for turning on or out the air when a car is coupled or uncoupled.

Referring especially to Fig. 3, it will be seen that the system is connected to the usual air supply tank 26, carried on the locomotive, by piping 27, which leads from the tank to the cab where it is connected to the engineer's three way valve 28.

In practice the device operates as follows: The system, as heretofore indicated, is com- 110

posed of old and well known parts already in use, these parts being arranged and combined to produce a very desirable result. The parts being in place, as described, as the 5 cars are coupled to the train the air pipes are connected in the usual way, the stop cocks turned on and the system is ready for use.

When the engineer has started his locomotive and the whole train is in motion, he 10 turns the three way valve 28 to admit air to the slack adjuster system. Air will then enter the various cylinders 8 through head 18 and will force the pistons 9 forward. This will cause piston rods 10 to move forward 15 and carry the buffer bars into contact with each other. The cars will then be held by the force of the compressed air in spaced relation so that one car may not run up on another.

20 In rounding curves, as indicated in Fig. 4, the buffer bars will still remain in contact throughout their length and air will flow from the cylinders on the inside of the curve to those on the outside.

25 When air is turned out from the system the springs 11 will force the pistons rearwardly thus allowing the cars to be easily coupled and uncoupled. It will also be noted that, when the train is to be brought to 30 a stop, after headway is sufficiently decreased the engineer may turn out the air and thus allow the train to gradually and easily slacken as it comes to a stop and be in position to allow the train to start without 35 throwing the whole load of the train on the locomotive at its first stroke. When a train is to be backed this system is also of great

advantage for, in this instance the engineer stops his train without turning out the air thus keeping the cars spaced apart. When 40 he starts to back the air is turned out allowing one car at a time to be taken up in the backing movement and, when all cars are in motion, the air is again turned on.

Having thus described the invention, what 45 is claimed as new and sought by Letters-Patent, is:

1. A train slack adjuster, comprising cylinders, pistons in the cylinders, piston rods extending from the pistons, buffer bars pivoted to the piston rods, fluid pressure means 50 for forcing the pistons to project the piston rods, and resilient means in each cylinder for retracting the pistons and separating the buffer bars upon release of the fluid pressure.

2. A train slack adjuster, comprising cylinders, pistons in the cylinders, piston rods, extending from the pistons, buffer bars, blocks sliding on the buffer bars, means for pivotingly connecting the piston rods to the sliding blocks, means for admitting fluid pressure to the cylinders to move the pistons and extend the piston rods, and a spring in each cylinder for retracting the pistons to 60 separate the buffer bars upon release of the fluid pressure.

In testimony that I claim the foregoing as my own, I have hereto affixed my signature in the presence of two witnesses.

NATHAN B. TEMPLE.
